UNITED STATES PATENT OFFICE

MEAD S. CARMICHAEL, OF SPARTA, WISCONSIN

ELEVATOR

Application filed October 10, 1928. Serial No. 311,478.

The present invention relates to a means for elevating fruit, vegetables and other materials, and has particularly to do with a lifting instrumentality suitable for use in canneries and the like.

The invention also relates to the combination with an instrumentality for elevating fruit and vegetables of a means for washing or cleansing such materials.

Heretofore, it has been common and customary to raise fruits and vegetables, say, for example, peas, from one level to another in the cannery during the canning operation, that is, from one floor to a higher floor, a conveyor bucket, by a belt conveyor, or similar devices. The opportunity to wash, rinse, or cleanse the peas during this operation has not existed, and the employment of mechanical elevating means has resulted in bruising, breaking, cutting, and otherwise damaging large numbers of the peas and of the other items during elevation.

The purpose of the present invention is to furnish an improvement in an elevating means and to render its utility greater by augmenting its scope by adding thereto a washing or rinsing effect. The provision of mechanical devices which will not tend to injure, harm, or hurt the tender peas or other fruit which may be placed in the elevator for lifting is a further aim carried out in the present construction.

These, and such other objects as may hereinafter appear, are attained by the novel construction, combination, and arrangement of elements disclosed in the device herein illustrated. A single embodiment of the invention is disclosed, and in the drawings, two sheets of which are submitted are hereby made a part of this specification:

Figure 1 is an elevation, a part of accessory apparatus being shown in section, the pumping devices and conduits therefrom being shown disjoined and in reduced proportion;

Figure 2 is a vertical section on the line 2-2 of Figure 1;

Figure 3 is a transverse section on the line 3-3 of Figure 1;

Figure 4 is a vertical section through one form of device for imparting intermittent

motion to the revolving cylinder employed in the elevator; and

Figure 5 is a view, partly in section and partly in elevation along the line 5-5 of Figure 1.

Like reference characters are used to designate similar parts in the drawings and in the specification.

Reference should be had first to Figures 1, 2, and 3. In a drum 10 which may be mounted upon legs 11 or otherwise suitably anchored are top and bottom plates 12 and 13. Within said drum 10 is a rotatable member 14 having top and bottom plates, 15 and 16, which are in juxtaposition with the top and bottom plates 12 and 13 of said drum 10, and which are of such a snug fit, thereagainst that they effectively prevent harmful seepage or flow of water or other fluid.

The cylinder 14 comprises a plurality of tubes, magazines, or shells, 17, spaced equidistantly apart, and in the present embodiment there are eight of these tubes. As indicated, tubes 17 may be formed of a section of piping or tubing reaching through the top and bottom plates 15 and 16. Said cylinders 17 are of a length substantially equal to the inside longitudinal dimension of drum 10. More or fewer tubes may be used.

For the purpose of rotating said cylinder 14 relatively to and within said drum 10, a shaft 18 is anchored or keyed in the top and bottom plates 15 and 16 of said cylinder, the upper end of the shaft 18 extending through the top plate 12 of said drum and terminating in a gear wheel 19.

Extending upwardly from said drum 10 is a discharge pipe 20 which is suitably affixed to said top plate 12 by the employment of an annular shouldered boss or flange 21 as is shown in Figure 2. Other means for fastening may be employed if desired.

Directly beneath the discharge pipe 20 is an inlet 22 to said drum 10, the inside diameter of the outlet 20 and inlet 22 and each cylinder 17 being the same. Said inlet 22 may be mounted in the same manner upon the bottom plate 13 as the discharge is mounted upon the top plate, there being shown an annular shouldered boss or flange 23 for this

purpose. It is essential for perfect operation that the outlet and inlet pipes 20 and 22 be in perfect alignment so that when the cylinders 17 register therewith there will be 5 a direct and uninterrupted passage for fluid from inlet 22 to outlet 20.

The cycle upon which the device operates includes the placing of material to be elevated in one of the cylinders 17 and then 10 forcing such material upwardly out of said cylinder through the discharge pipe 20 by an influx of displacing fluid from the inlet 22. There must be means for rotating said cylinders 17 to bring them one at a time into 15 registry with the inlet and discharge pipes 22 and 20, and means for loading said cylinders or tubes 17 anterior to the time they are brought into such registry.

For this latter purpose, a hopper 24 is disposed upon the top plate 12. When the cylinders or tubes 17 are of small diameter, it is preferable that the discharge section of such hopper have such a dimension that it bridges over parts of two of the tubes 17 25 when the cylinder 14 is stationary. If the cylinders or tubes 17 are of larger diameter, it is better that the hopper 24 register directly with only one tube 17 when cylinder 14 is stationary. The material which is fed 30 into the cylinders 17 through hopper 24 is fed thereinto in any regulated manner desired.

After a tube 17 has registered in the position whereby water is forced therethrough 35 to clear it of its contents, the entire contents of vegetable matter, such as peas, is discharged from such tube, but the tube 17 is filled with the displacing water. This water or fluid must be discharged in order 40 to facilitate the rapid and efficient reloading of the tube. Were the tubes 17 to remain filled with fluid, it would be with difficulty only that each could be reloaded, and there would be as an incident to such loading, if 45 the material to be elevated was lighter than water, considerable flotation which would be most annoying, and where the goods to be elevated had a specific gravity greater than the elevating fluid, there would be an over- 50 flow of fluid up through the loading hopper 24.

It is advisable to remove all of such displacing water or the greater portion thereof. Gravity discharge of such fluid for such purpose is not believed to be entirely efficient and is wasteful.

For these reasons, at any suitable place adapted to register with one of the tubes 17 which has been discharged of material and 60 registering therewith when such cylinder is in stationary position, an unloader or fluid discharge pipe 25 is provided, which pipe 25 is adapted to provide a source of supply to a pump 26. An annular shouldered flange 65 or boss 27 is provided upon plate 13 to seat

said pipe 25 as shown. The pump 26 is adapted to draw water from the tubes 17 one at a time and when in registry with the discharge outlet 25.

A second or main pump 28, both pumps 26 70 and 28 being shown as of the rotary type, and pump 26 are keyed to a single shaft 29 suitably mounted upon brackets 30, 31 and 32 and are adapted to be driven by any driving belt passing around the pulley 33 intermediate the brackets 30 and 31. Pumps 26 and 28 are suitably secured upon brackets 34 and 35 in juxtaposition to brackets 31 and 32.

The circulation of fluid through the main pump 28 is from a source of supply of water 80 36, which may be the city supply, through a conduit 37, to the pump 28, from the pump through a conduit 38 to the bottom of the drum 10, said conduit 38 terminating in the inlet pipe 22, and at periodic or timed intervals upwardly through a tube 17 and out through the discharge pipe 20 to a hopper 39 comprising a screen 40 to receive the material which has been elevated, such screen being disposed at a point above the bottom 90 of the hopper 39 which provides a trough 41 having a discharge pipe 42 therefrom.

In the conduit 37 leading from the source of supply 36 to the pump 28 is a main valve 43, which is adapted to be employed for the 95 purpose of controlling the supply of water to the device.

Conduit 38 is adapted to receive in addition to the flow from pump 28, the discharge from pump 26 so that the clean water taken from cylinder 17 may be again used as a part of the elevating fluid.

In the conduit 38 from the pumps 26 and 28 to the drum 10 is a gate valve 44. The purpose of this valve is to prevent a back- 105 flow of fluid carrying vegetable matter into either of the pumps 26 and 28 upon the shutting down of the pumps or an accident closing off the supply of fluid.

One of the marked novelties of the present 110 device is the fact that the vegetable material when projected upwardly out of the tubes 17 and through the discharge pipe 20 is most thoroughly washed or rinsed. The force of discharging fluid is such that the material 115 to be elevated which anteriorly has been closely packed and probably not thoroughly washed because, at all times, in surface contact with adjacent particles of a similar nature, is spread apart by the force of the elevating fluid and the great excess thereof so that each elevated particle is separated from each other particle and the entire surface of the pea or other vegetable matter is brought 120 into direct contact with fresh water under pressure whereby any remaining dirt or removable material thereon may be removed. In the illustrated form of the device, the fluid, after it has been once projected through the pumps 26 and 28 is not again used, thus 130

insuring an efficient washing for the fruit or vegetable matter which is elevated.

As has already been indicated, the magazine 14 or tubes 17 is rotated with an intermittent motion, one tube 17 at a time being moved into joint registration with the inlet 22 and outlet 20 and another cylinder 17 being brought into registration with the unloading discharge pipe 25 preparatory to loading from hopper 24.

In the loading position, it is usual, as has been pointed out, to have one or two of the tubes 17 beneath the lower end of the hopper 24 so that adequate loading thereof can be had. The movement of the material to be elevated under the loading influence of gravity (the loading means employed,) is generally much slower than the discharge of the tubes 17 under the force of pump 26.

The intermittent motion preferred for the operation of the device may be obtained in a variety of ways. Only one form or method is disclosed. This is disclosed in Figures 1, 4, and 5, and it is identical with the means disclosed in applicant's prior application, Serial No. 249,035, filed January 24, 1928, and entitled "Elevator". A brief description thereof will be given.

Disposed upon the drum 10 are two brackets 45 in which is journaled a shaft 46 having a gear 47 meshing with the gear 19 upon the vertical shaft 18 anchored or keyed to the two revolving plates 15 and 16. Upon that end of said shaft 46 which extends beyond the drum 10, the right-hand side in Figure 1, is a sleeve 48, the inner end of which is formed or equipped with a circular plate 49. Keyed upon said sleeve is a relatively large belt pulley 50. Pivoted to the sleeve 48 at the outer face of the plate 49 is a lever 51 equipped with an inwardly extending pin 52 movable through a notch 53 at the periphery of the plate 49.

Such lever 51 is limited in its swinging movements by a horizontal guide plate 54 secured to the periphery of the plate 49 and formed with a horizontal slot 55 through which the lever 51 is free to move as is shown in Figure 4.

By a retractile spring 56, said lever is normally pulled in a direction away from the plate 49 so that the pin 52 will be drawn substantially out of the notch 53 by said spring 56 being of the coil type and anchored at its ends to the pulley 50 and to said lever 51. To produce a swinging movement of the lever 51 against the action of the spring 56 and the consequent projection of the pin 52 through the notch 53, there is upon the drum 10 directly beneath the plate 49 a transversely extending arcuate shaped track 57 formed with an upstanding side wall 58. At the upper end of the track 57, wall 58 extends considerably beyond such track, as is clearly indicated in Figure 5, and flares outwardly as

is indicated at 59. Any suitable bracket such as that shown may be employed to hold the track 57 upon drum 10.

Thus, the sleeve 48 carrying the notched plate 49 and lever 51 when rotated in a direction to move said lever 51 toward the upper end of the track 57, will cause engagement between the outer end of the lever 51 and the flared end 59 of the track thereby causing said lever 51 to be moved inwardly, thus forcing the pin 52 through the notch 53. The track 57 will cause the lever 51 to be held in such position during a predetermined degree of the rotation of the plate 49.

Upon the shaft 46 and keyed thereto in spaced relation to the plate 49 is a second circular plate 60 having its inner face studded with horizontally extending pins 61, one for each of the tubes 17, that will be engaged one at a time by the pin 52 of the lever 51 when the lever 51 is moved inwardly by its engagement with the track 57. This engagement will cause the rotation of the plate 60 and consequently the shaft 18 will be turned a predetermined distance, an eighth turn in this instance, thus rotating the revolving cylindrical unit 14 within the drum 10. The degree of the movement of cylinder 14 is so regulated that accurate registration is obtained, with each advance of such revolving cylinder, between one tube 17 and the inlet and outlet 22 and 20.

Immediately the lever 51 shall have become disassociated with the track 57, the spring 56 between the pulley 50 and lever 51 will withdraw said lever 51, concurrently moving the pin 52 out of the notch 53 and disengaging said pin 52 from one of the pins 61 upon plate 60.

It is during the period of time required for an almost complete rotation of the pulley 50 that the cylinder 14 within the drum 10 is stationary, and it is during this interim of time that fluid is forced from the inlet 22 through one of the tubes 17 and through the outlet 20, and that the displacing fluid is withdrawn from another of the tubes 17, this tube being intermediate the point it registers with said inlet 22 and outlet 20 and the approach of the loading station 24.

I claim:

1. In a hydraulic elevating device for articles of appreciable size, a unit comprising a plurality of chambers, a liquid inlet pipe communicating with the unit and adapted to discharge into said chambers, a discharge pipe extending therefrom, means whereby said chambers may be loaded, and suction means for removing liquid from said chambers.

2. In a hydraulic elevating device, a drum having an aperture inlet in its bottom wall and an aperture in its top wall, a unit mounted within the drum and including a plurality of vertically extending material carrying

tubes, means whereby the tubes may be loaded, means for rotating the unit, a pump, a conduit to the aperture in the bottom wall of said drum whereby liquid under pressure is adapted to be projected through the various tubes when the same are brought into registration with said apertures in the drum, and suction means for withdrawing undischarged liquid from said tubes.

10 3. In a hydraulic elevating device, a drum, a unit mounted for rotation within the drum and including a plurality of vertical tubes, a liquid inlet pipe communicating with the bottom of the drum, an outlet pipe extending 15 from the top of the drum and arranged for registration with the tubes of the unit one at a time, means whereby the tubes may be loaded, means for rotating the unit, a source of liquid under pressure adapted to discharge 20 material from the tubes, and suction means whereby undischarged liquid remaining in said tubes may be withdrawn therefrom and again forced thereinto.

4. In a hydraulic elevating device, a drum, 25 a unit mounted for rotation within the drum and including a plurality of vertical tubes, a liquid inlet pipe communicating with the bottom of the drum, an outlet pipe extending from the top of the drum, means whereby the 30 tubes may be loaded, means for rotating the unit, a source of liquid under pressure, and suction means for withdrawing undischarged liquid remaining in said tubes and for adding the withdrawn liquid to said source of 35 sup-

ply.

5. In a hydraulic elevating device, a closed drum, a unit mounted for rotation within the drum and including a plurality of vertical tubes, a liquid inlet pipe communicating with the bottom of the drum, a liquid outlet pipe 40 from the top of said drum, a pump whereby liquid under pressure is adapted to discharge the material from the tubes when the same are disposed between said inlet and outlet pipes, 45 and a pump providing suction means for removing undischarged liquid remaining in said tubes.

6. In a hydraulic elevating device, a drum, 50 a unit mounted for rotation within the drum and including a plurality of vertical tubes, a liquid inlet pipe communicating with the bottom of the drum, an outlet pipe extending from the top of the drum, means whereby the tubes may be loaded, means for rotating the 55 unit, a source of liquid, and pump means for forcing such liquid under pressure through said tubes when the same are disposed between said inlet and outlet pipes and for withdrawing undischarged liquid from said tubes 60 after the same have passed out of registration with said inlet and outlet pipes.

7. A hydraulic elevating device comprising 65 a pump for supplying liquid under pressure, a pipe from said pump, a liquid outlet pipe, a

70 rotor including a plurality of parallel mate-
rial carrying tubes, means whereby said tubes may be loaded, suction means for withdraw-
ing undischarged liquid from said tubes, and
means for moving said rotor between said
75 pipe from said pump and said outlet and into
association with said liquid withdrawing
means.

8. A hydraulic elevating device comprising
75 a pump for supplying liquid under pres-
sure, a pipe for the liquid under pressure,
an outlet pipe for such liquid, a plurality of
parallel tubes intermediate said source of
liquid and said outlet, suction means for
80 withdrawing undischarged liquid from
said tubes, and means for imparting periodic
movement to said tubes, said last-mentioned
means registering said tubes one at a time
with said pipe for liquid under pressure and
said outlet pipe and said suction means.

9. In a hydraulic elevating device, a unit 85 comprising a plurality of tubes, a casing
therefore having an inlet port and an outlet
port, means for moving said tubes one at a
time past said inlet and said outlet ports, and
suction means for freeing said tubes from 90
liquid contents.

10. In a hydraulic elevating device, a drum,
a unit mounted for rotation within said drum
and comprising a plurality of parallel tubes,
there being a liquid inlet port through the 95
bottom of said drum, and a liquid outlet port
from said drum, means for rotating said
unit, a pump providing a source of liquid un-
der pressure the liquid therefrom being
adapted to pass through said tubes one at a 100
time when disposed between said inlet port
and said outlet port, and suction means op-
erable when said tubes are not in registry with
said inlet and said outlet ports for with-
drawing the undischarged liquid contents of 105
said tubes.

11. An elevating device comprising a drum,
a unit of parallel tubes mounted for move-
ment within said drum, said drum having
a liquid inlet port and an outlet port opposite 110
said inlet port, means for imparting inter-
mittent motion to said unit to register said
tubes one at a time with said inlet and said
outlet ports, a loading station for said tubes,
there also being an opening in said drum for 115
releasing liquid from said tubes, said opening
being at a point intermediate said inlet and
outlet ports and said loading station, and
pumping means comprising a member adapt-
ed to force liquid through said tubes and a 120
second member withdrawing liquids from
said tubes through said opening and to aug-
ment the flow of liquid under pressure
through said tubes.

MEAD S. CARMICHAEL. 125
